INVENTOR.
Charles H. Kaiser:

BY
Frautzl and Richards,
ATTORNEYS.

UNITED STATES PATENT OFFICE.

CHARLES H. KAYSER, OF MONTCLAIR, NEW JERSEY.

AUTOMATIC TRAFFIC-SIGNAL MECHANISM.

Application filed January 9, 1924. Serial No. 685,079.

To all whom it may concern:

Be it known that I, CHARLES H. KAYSER, a citizen of the United States, residing at Montclair, in the county of Essex and State 5 of New Jersey, have invented certain new and useful Improvements in Automatic Traffic-Signal Mechanism; and I do hereby declare the following to be a full, clear, and exact description of the invention, such as 10 will enable others skilled in the art to which it appertains to make and use the same, reference being had to the accompanying drawings, and to characters of reference marked thereon, which form a part of this 15 specification.

This invention relates to an automatic traffic signal mechanism for use at city street and highway intersections.

The invention has for its principal object 20 to provide a simple, durable and automatic mechanism for actuating traffic signals, which is of comparatively low initial cost, and which may be operated and maintained at very small cost.

25 The invention has for a further object to provide a novel traffic signal device having visible signal means for both day and night, and also audible signal means, together with automatic means for actuating 30 the several signals; and the invention has for a still further object to provide in connection with the automatic signal actuating means, a novel arrangement of means whereby the time intervals during which 35 given signals are made may be regulated or controlled as necessity may require.

Other objects of this invention, not at this time more particularly enumerated, will be clearly understood from the following 40 detailed description of the same.

With the various objects of the invention in view, the same consists, primarily, in the novel automatic traffic signal mechanism hereinafter set forth; and, the invention 45 consists, furthermore, in the novel arrangements and combinations of the various devices and parts, as well as in the details of the construction of the same, all of which will be hereinafter more fully described, and 50 then finally embodied in the claims appended hereto.

The invention is clearly illustrated in the accompanying drawings, in which:—

55 Figure 1 is an elevation of the novel automatic traffic signal mechanism, made according to and embodying the principles

of this invention; Figure 2 is a part longitudinal section of the same, showing the actuating mechanism in elevation, said view being drawn on an enlarged scale; Figure 60 3 is a vertical longitudinal section, taken on line 3—3 in said Figure 2; Figure 4 is also a vertical longitudinal section, taken on line 4—4 in said Figure 2; Figure 5 is a detail side elevation of the signal post, showing 65 the legend bearing semaphore arm collapsed or turned down to inactive position; Figure 6 is one face view of the trip wheel of the signal actuating mechanism; Figure 7 is a detail of the bell or gong trip wheel; Figure 8 is a detail perspective of the weight 70 supporting trip lever; Figure 9 is a wiring diagram of the electrical circuits for the motor and lighting system of the signal mechanism; Figure 10 is a fragmentary detail of a modified form of signal actuating mechanism; and Figure 11 is a detail horizontal section of the latter, taken on line 75 11—11 in said Figure 10.

Similar characters of reference are employed in all of the hereinabove described views, to indicate corresponding parts.

Referring now to said drawings, the reference character 12 indicates a suitable base upon which the traffic signal mechanism is supported. Preferably this base is of greater diametric dimension, than the traffic signal mechanism supported thereon, and is provided at its upper periphery with an outwardly projecting flange, lip or fender 80 portion 13, which tends to prevent vehicles, that may accidentally collide with the base, from riding up on the latter to the possible injury of the traffic signal mechanism supported thereon. Said base 12 may be made 85 of stone, concrete, cast metal or of any other material convenient and suitable for the purpose.

90 Centrally fixed upon said base 12 is a housing 14 of any suitable design, the side walls of which are provided with removable panels or doors 15 giving access to the interior of the housing within which the automatic signal actuating device of the mechanism are arranged.

95 Secured within said housing 14, so as to be disposed horizontally therein, is a bridge plate 16. Mounted upon said bridge plate 16, so as to extend upwardly therefrom and outwardly through the top of said housing 14, is a hollow vertical post 17. Rotatably supported on said post 17 is a sleeve or hol-

- low shaft 18, the lower end of which extends downwardly into said housing 14; the same having an annular stop-shoulder 19 which engages the top of said housing 14 to prevent downward displacement thereof from normal operative position, whereby the same extends vertically upward over said post 17 above said housing. Secured upon the interior lower end of said sleeve or hollow shaft 18 is a bevel gear 20.
- Attached to the upper end of said post 17 is a cap-piece 21 provided with an electric lamp-socket 22, to which is fitted a suitable electric lamp 23.
- Secured upon the upper end of said sleeve or hollow shaft 18, so as to turn therewith, is a lamp-housing 24 having four apertured sides. Arranged in the apertures of one pair of diametrically opposite sides of said lamp-housing are signal lens 25 of glass, or other transparent material, suitably colored, to provide a signal indication visible at night; as, for example, a white, yellow or green color to indicate a clear passage to approaching vehicles. Arranged in the apertures of the other pair of diametrically opposite sides of said lamp-housing are signal lens 26 of glass, or other transparent material, suitably colored, to provide a signal indication visible at night; as, for example, a red color to indicate that passage is closed to approaching vehicles.
- Mounted on said hollow shaft 18, below said signal lamp-housing 24, are a set of signal semaphore devices adapted to bear signal legends visible in day-light. Said semaphore devices are preferably constructed and mounted in the following manner. Fixed upon said hollow shaft 18 is a sleeve 27. Projecting outwardly from said sleeve 27, in positions spaced downwardly a suitable distance from the upper end of the latter, are four pair of perforate ears or fulcrum lugs 28. The semaphore devices preferably comprise a pair of rectangular frames 29 open at their upper margins for the insertion therein of legend bearing placards 30, and a pair of like rectangular frames 31 also open at their upper margins for the insertion therein of legend bearing placards 32. The frames 29 and 31 are provided at their lower inner corners with perforate ears 33 which are respectively received between the respective pair of fulcrum lugs 28, to which they are pivotally connected by a suitable hinge pin or pintle 34. Projecting from said sleeve 27, at the upper end thereof, are socket lugs 35, which embrace and hold the upper inner corners of the respective frames 29 and 31, when the latter are turned up to operative positions. Each frame 29 and 31 is provided intermediate the ends of its lower margin, with a perforate ear 36. Vertically slidable upon the shaft 18, below the sleeve 27, is a slide-collar 37, which is also provided with four pairs of perforate ears or lugs 38. Pivotally interconnected between the respective lugs 38 and the ears 36 of said frames 29 and 31 are links 39. When in operative position, the respective pairs of frames 29 and 31 are raised so that the same extend outwardly from the shaft 18, as shown in Figures 1 and 2. The pair of diametrically opposite frames 29 are provided with the placards 30 upon which is inscribed a suitable legend, such as the word "Stop" to indicate that passage is closed to approaching vehicles; while the other pair of diametrically opposite frames 31 (which extend at right angles to the frames 29) are provided with the placards 32 upon which is inscribed a suitable legend, such as the word "Go" to indicate that passage is open to approaching vehicles. When it is desired to indicate that traffic regulations are suspended, and the signal mechanism is not working, the semaphores or frames, with their legend bearing placards, are turned downward (as shown in Figure 5 of the drawings), such position of the semaphores or frames being attained by sliding downward the slide-collar 37 against a stop-collar 40 which is fixed on the shaft 18, thus causing the links 39 to pull or swing the semaphores or frames into said downwardly turned inoperative position.
- Secured upon the shaft 18, adjacent to its lower end, but above the top of the housing 14, are one or more outwardly projecting hand levers 41, by means of which the signal device may be actuated and controlled by hand, should any occasion render hand manipulation thereof desirable.
- Supported upon said bridge plate 16 is an upstanding supporting plate 42, disposed adjacent to said post 17. Projecting from said supporting plate 42 is a fixed stud-shaft 43, upon which is rotatably mounted a sleeve 44. Fixed on the outer end of said sleeve is a ratchet-wheel 45, and fixed on the inner end of said sleeve is a spur gear 46. Extending through said supporting plate 42, so as to be journaled therein, is a shaft 47, upon the outer end of which is fixed a spur gear 48 which meshes with and is driven by the aforesaid spur gear 46. Fixed upon the inner end of said shaft 47 is a bevel drive gear 49, which meshes with said bevel driven gear 20 which is fixed upon the lower end of said hollow shaft 18, within the interior of the housing 14. Pivotally supported, so as to extend beneath said bridge plate 16, is a trip-lever 51, to the outer free end 50 of which is suspended a weight 52 or other suitable means for exercising a downwardly swinging pull upon said trip-lever. The lower margin of said trip-lever 51 is suitably shaped to provide a trip-shoulder or step 53. Pivotally sup-

ported from a fulcrum post 54, mounted on said supporting plate 42, is a secondary lever 55, which is positioned above the aforesaid ratchet wheel mechanism. Interconnecting 5 said trip-lever 51 with said secondary lever 55 is a link 56, said bridge plate 16 having a slot or opening 57 through which said link 56 extends and moves. Pivottally connected with said secondary lever 55, at a point intermediate 10 the ends of the latter, is a drive-pawl 58, the free end of which operatively cooperates with said ratchet-wheel 45, at one side of the latter. Also pivotally mounted on said fulcrum post 54 is a stop-pawl 59, provided at its free end with an anti-friction roller 60, which cooperates with the teeth of said ratchet-wheel 45, on the opposite side of the latter. Interconnected between said drive-pawl 58 and said stop-pawl 59 is a pull-spring 61 the tension of which tends to 20 keep said respective pawls in operative engagement with the respective sides of said ratchet wheel. If desired an auxiliary pull-spring 62 may be interconnected between the free end of said stop-pawl 59 and a fixed point on said bridge-plate 16, the tension of which serves, in addition to that of the spring 61 to operatively maintain said stop-pawl 59 in engagement with said ratchet-wheel 30 45.

The reference character 63 indicates a pair of bearing members or shaft-hangers, which depend from the underside of said bridge-plate 16. Rotatably supported by said shaft-hangers 63 is a shaft 64, upon which is fixed a worm-gear 65. Also fixed on said shaft 64 is a worm 66. Rotatably mounted on a stud-shaft 67, which is fixed to a bracket member 68 secured to and projecting downwardly from the underside of said bridge-plate 16, is a trip-wheel 69, having at its circumference worm-gear teeth 70 which mesh with said worm 66, whereby said trip-wheel is rotated. Projecting from the outer face of said trip-wheel is one or more trip-studs 71 in the form of anti-friction rollers; said trip-wheel having a plurality of circularly disposed and suitably spaced apart openings or sockets 72, whereby two or more trip studs may be adjusted in position relative one to another, for purposes to be subsequently set forth.

The means for driving the automatic signal controlling and actuating mechanism, above described, may comprise any suitable source of power, but, preferably, a comparatively small electric motor 73 is employed, which is mounted within the housing 14, and the drive shaft 74 of which is provided with a drive worm 75, which meshes with and drives said worm-gear 65.

The audible signal device with which the mechanism may be equipped, comprises, preferably, a bell or gong 76, which may be suitably supported in connection with a

bracket 76'. Suitably fulcrumed, also in connection with one of said shaft-hangers 63, is a bell-clapper or striker 77, which is provided with an actuating arm 78 arranged to extend adjacent to the rear face of said trip-wheel 69. Said trip-wheel is provided on its rear face with one or more trip-studs 79 to engage and actuate the arm 78 for the striker 77 when said trip-wheel is rotated. Provided in the rear face of said trip-wheel 70 69 is a circular row of openings or sockets 80 whereby two or more trip-studs 79 may be adjusted in position relative one to another, for purposes to be subsequently set forth.

The electrical connections or wiring for supplying current to the motor and to the illuminating lamp for the night signal means, may, of course, be variously arranged, in any manner found expedient; it is, preferable, however, to arrange within the housing 14 a switch-board 81, with a motor control switch 82 and a light control switch 83, with suitable wiring leading therethrough from the source of supply to both the motor and lamp. In Figure 9 of the drawings, there is shown a wiring diagram, which illustrates one practical arrangement of the lighting and motor circuits. In the said diagram the source of supply is shown, for purposes of illustration only, as a battery 84, from which extends the feed-wire 85 to the lamp 23, the returned wire 86 extending from the lamp through the switch 83 back to the battery 84. Extending from said feed-wire 85 leading from the battery 84 is a branch feed-wire 85, which leads through the control switch 82 to one pole of the motor 73, and extending from the opposite pole of said motor 73 is a return wire 86' which connects with the main return wire 86 leading back to said battery 84. 90 95 100 105

The operation of the automatic signal actuating mechanism, in the form above described, is as follows:—

Current being supplied to the motor 73, the operation thereof drives the worm gear 65 and shaft 64 to rotate the worm 66, and thereupon to in turn rotate the trip-wheel 69. The worm and gear transmission mechanism thus provided constitutes a reduction gearing, which may be so designed as to produce or transmit from a normal predetermined motor speed, a rotative speed to said trip-wheel 69 of any desired predetermined time per revolution. For the sake of illustration, we will assume that through said reduction gearing the trip-wheel 69 is caused to make one complete revolution every two minutes, or one hundred and twenty seconds. We will also assume that two main trip-studs 71 are provided on the outer face of the trip-wheel 69. If it is desired to alternately produce "Stop" and "Go" signals at equal time intervals, said trip-studs 71 are spaced apart equally, or one 110 115 120 125 130

hundred and eighty degrees, so that the signals will be so actuated that traffic will be alternately passed or stopped for equal time periods as to each intersecting street at the junction of which the mechanism is installed. If, however, the traffic is normally heavier on one of the intersecting streets than it is on the other, so that it is desired to lengthen the time period of permitted passage thereof relative to the stopped period over said first mentioned street, while at the same time correspondingly lengthening the stopped period relative to the passing period permitted on the other intersecting street, then the trip-studs 71 are adjusted in relation one to the other, whereby such desired control is obtained. For example, if the trip-wheel 69 completes its rotation in two minutes, and it is desired to pass traffic on one street and stop traffic on the other street for a period of eighty seconds, while only permitting traffic to pass on the latter street while stopped on the former street for a period of forty seconds, then the trip-studs 71 are so adjusted relative to each other that intermediate the same on one side there is an interval of two-hundred and forty degrees, and intermediate the same on the other side there is an interval of one-hundred and twenty degrees, to the end that the period of display of the proper signals to the traffic on the respective streets will be alternately and intermittently timed at the desired ratio. The latter described adjustment of the stop-studs 71 is illustrated in Figure 2 of the drawings.

The trip-wheel 69 is constantly driven, and by its rotation the stop-studs 71 are carried into engagement with the trip-lever 51 forward of the shoulder or step 53. The arc of movement of the trip-stud 71 in contact with the trip-lever 51, tends to raise the latter against the pull of gravity exerted thereon by the weight 52. When the trip-lever 51 is thus swung upwardly, the upward swinging motion thereof is transmitted by the link 56 to the secondary lever 55, thereby lifting the drive-pawl 58, to cause the latter to ride upwardly over one tooth of the ratchet-wheel 45. By the time the drive-pawl is thus lifted to engage a succeeding or next tooth of the ratchet-wheel 45, the trip-stud 71 approaches the shoulder or step 53 of the trip-lever 51. As the trip-stud 71 passes the shoulder or step 53, the trip-lever 51 drops, under the influence of the force of gravity exercised on the weight 52, and the trip-lever thus transmits through the link 56 a downward swinging movement to the secondary lever 55, and thereby causes the drive-pawl 58 to rotate the ratchet-wheel of a distance equal to the movement of one tooth thereof. The rotation thus imparted to the ratchet-wheel 45 is transmitted

65 through the spur-gears 46 and 48, and thence

through the bevel gears 49 and 20 to cause a quarter rotation of the signal carrying shaft 18, thus changing the display of its signals relative to the respective intersecting streets, in a manner already familiar to those acquainted with the operation of traffic signal devices. Preferably the ratchet-wheel 45 possesses eight teeth, so that each operation thereof it is moved with the spur gear 46 one eighth of a revolution. The ratio between the spur gear 46 and spur gear 48 is preferably one to two, and consequently the transmitted movement results in turning the spur gear 46 and the bevel gear 49 one fourth of a revolution, and since the ratio between the bevel gear 49 and bevel gear 20 is even, it follows that the signal carrying shaft 18 will be intermittently and alternately rotated by quarter-revolution impulses, to intermittently display the "Stop" and "Go" signals thereof alternately to the respective intersecting streets at the junction of which the novel signal mechanism is installed.

Referring now to Figures 10 and 11 of the drawings, there is illustrated thereby a simple form of automatic signal actuating mechanism, which is adapted for use where the time intervals, at which the signals are to be alternately and intermittently displayed, are equal. This modified form of actuating mechanism, comprises a vertical shaft 87 upon which is fixed a worm gear 88 which is driven by the worm 88' on the drive shaft 89 of an electric motor 90, or which may be otherwise driven if desired. Fixed on the lower end of the signal carrying shaft 18 is a female Geneva gear 91, and fixed on said shaft 87 is a male Geneva gear 92 which meshes with and drives said female Geneva gear 91. It will be understood that the Geneva movement thus provided will produce an intermittent rotation of the signal carrying shaft 18, so that during the period of "dwell" of the female Geneva gear, the signal will be held stationary and effective as to the respective intersecting streets; at the junction of which the mechanism so constructed is installed.

I am aware that some changes may be made in the arrangements and combinations of the various devices and parts, as well as in the details of the construction of the same, within the scope of my present invention as set forth in the foregoing specification, and as defined in the appended claims. Hence, I do not limit my invention to the exact arrangements and combinations of the several devices and parts as described in said foregoing specification, nor do I confine myself to the exact details of the construction of said parts as illustrated in the accompanying drawings.

I claim:

1. An automatic traffic signal mechanism,

- comprising a supporting means provided with a vertically disposed rotatable shaft, visible signal means supported and operated by said shaft, means for imparting 50 rotative impulses to said shaft to alternately display desired signals to the traffic to be controlled, the same including a ratchet-wheel, a gravity controlled lever mechanism including a drive-pawl for actuating said ratchet-wheel, a rotary-trip-wheel, said trip-wheel having a plurality of trip-studs for raising and tripping said lever mechanism, means whereby said trip-studs may be adjusted in relation to each other to regulate the time of their active cooperation with said lever mechanism during each rotation of said trip-wheel and means for rotating said trip-wheel.
2. An automatic traffic signal mechanism, comprising a supporting means provided with a vertically disposed rotatable shaft, visible signal means supported and operated by said shaft, means for imparting rotative impulses to said shaft to alternately display desired signals to the traffic to be controlled, the same including a ratchet-wheel, a gravity controlled lever mechanism including a drive-pawl for actuating said ratchet-wheel, a rotary trip-wheel, said trip-wheel having a plurality of trip-studs for raising and tripping said lever mechanism, means whereby said trip-studs may be adjusted in relation to each other to regulate the time of their active cooperation with said lever mechanism during each rotation of said trip-wheel, means for rotating said trip-wheel, an audible signal element, means for sounding said audible signal element, a plurality of additional trip-studs on said trip-wheel to cooperate with and actuate said sounding means, and means for relatively adjusting said additional trip-studs in correspondence with the adjustment of said first mentioned trip-studs whereby said audible signal is actuated simultaneously with each actuation of said visible signals.
3. An automatic traffic signal mechanism, comprising a housing, a post supported within said housing to project vertically and exteriorly therefrom, a hollow shaft rotatably supported on said post, an illuminated signal means carried by said hollow shaft, signal semaphores also carried by said hollow shaft, means for imparting rotative impulses to said shaft to alternately display desired illuminated signal means and signal semaphores to the traffic to be controlled, said rotation imparting means including a ratchet-wheel, a pivoted trip-lever, a weight attached to the end of said trip-lever for producing operative downward oscillations thereof, a pivoted secondary lever, a link interconnecting said secondary lever with said trip-lever, said secondary lever having a spring-controlled drive-pawl to actively co-
- operate with said ratchet-wheel, and means for intermittently raising and tripping said trip-lever, said latter means being adjustable to relatively vary successive time intervals at which said trip-lever is actuated thereby.
4. An automatic traffic signal mechanism, comprising a housing, a post supported within said housing to project vertically and exteriorly therefrom, a hollow shaft rotatably supported on said post, an illuminated signal means carried by said hollow shaft, signal semaphores also carried by said hollow shaft, means for imparting rotative impulses to said shaft to alternately display desired illuminated signal means and signal semaphores to the traffic to be controlled, said rotation imparting means including a ratchet-wheel, a pivoted trip-lever, a weight attached to the end of said trip-lever for producing operative downward oscillations thereof, a pivoted secondary lever, a link interconnecting said secondary lever with said trip-lever, said secondary lever having a spring-controlled drive-pawl to actively cooperate with said ratchet-wheel, means for intermittently raising and tripping said trip-lever, an audible signal element, and means for actuating said audible signal in company with each operative movement of said trip-lever for the purposes described.
5. An automatic traffic signal mechanism, comprising a housing, a post supported within said housing to project vertically and exteriorly therefrom, a hollow shaft rotatably supported on said post, an illuminated signal means carried by said hollow shaft, signal semaphores also carried by said hollow shaft, means for imparting rotative impulses to said shaft to alternately display desired illuminated signal means and signal semaphores to the traffic to be controlled, said rotation imparting means including a ratchet-wheel, a pivoted trip-lever, a weight attached to the end of said trip-lever for producing operative downward oscillations thereof, a pivoted secondary lever, a link interconnecting said secondary lever with said trip-lever, said secondary lever having a spring-controlled drive-pawl to actively cooperate with said ratchet-wheel, a rotary trip-wheel having trip means for raising and tripping said trip-lever, and means for rotating said trip-wheel.
6. An automatic traffic signal mechanism, comprising a housing, a post supported within said housing to project vertically and exteriorly therefrom, a hollow shaft rotatably supported on said post, an illuminated signal means carried by said hollow shaft, signal semaphores also carried by said hollow shaft, means for imparting rotative impulses to said shaft to alternately

- display desired illuminated signal means and signal semaphores to the traffic to be controlled, said rotation imparting means including a ratchet-wheel, a pivoted trip-lever, a weight attached to the end of said trip-lever for producing operative downward oscillations thereof, a pivoted secondary lever, a link interconnecting said secondary lever with said trip-lever, said secondary lever having a spring-controlled drive-pawl to actively cooperate with said ratchet-wheel, a rotary trip-wheel, said trip-wheel having a plurality of trip-studs for raising and tripping said trip-lever, means whereby said trip-studs may be adjusted in relation to each other to regulate the time of their active cooperation with said trip-lever during each rotation of said trip-wheel, and means for rotating said trip-wheel.
7. An automatic traffic signal mechanism, comprising a housing, a post supported within said housing to project vertically and exteriorly therefrom, a hollow shaft rotatably supported on said post, an illuminated signal means carried by said hollow shaft, signal semaphores also carried by said hollow shaft, means for imparting rotative impulses to said shaft to alternately display desired illuminated signal means and signal semaphores to the traffic to be controlled, said rotation imparting means including a ratchet-wheel, a pivoted trip-lever, a weight attached to the end of said trip-lever for producing operative downward oscillations thereof, a pivoted secondary lever, a link interconnecting said secondary lever with said trip-lever, said secondary lever having a spring-controlled drive-pawl to actively cooperate with said ratchet-wheel, a rotary trip-wheel, said trip-wheel having a plurality of trip-studs for raising and tripping said trip-lever, means whereby said trip-studs may be adjusted in relation to each other to regulate the time of their active cooperation with said trip-lever during each rotation of said trip-wheel, means for rotating said trip-wheel, an audible signal element, means for sounding said audible signal element, a plurality of additional trip-studs on said trip-wheel to cooperate with and actuate said sounding means, and means for relatively adjusting said additional trip-studs in correspondence with the adjustment of said first mentioned trip-studs whereby said audible signal is actuated simultaneously with each actuation of said illuminated and semaphore signal devices.
- In testimony, that I claim the invention set forth above I have hereunto set my hand this 8th day of January, 1924.
- CHARLES H. KAYSER.
